ELMER C. HALL, OF FAIRFIELD, CONNECTICUT

PAINTBRUSH HOLDER

Application filed October 2, 1929. Serial No. 396,705.

This invention relates to a paint brush holder and has for an object to provide a means for holding the brushes when not in use in such a manner as to prevent the bristles from either hardening or getting out of shape. As is well known, at present, a common manner of storing paint brushes is to place them in an old paint can containing linseed oil, but this very shortly spoils the brushes because the bristles are soon bent laterally out of shape.

A further object of this invention is to provide a V-shaped trough made of a single piece of material, preferably sheet metal, which may be economically manufactured and to provide a means for detachably holding paint brushes in storage in said trough, linseed oil or other preserving liquid being placed in said trough to preserve the bristles, the brushes being so supported that the weight of the brushes tends to bend the bristles to the desired chisel shape, as contrasted with the old paint can wherein the weight of the brush bends the bristles laterally out of shape.

With the foregoing and other objects in view, this invention comprises the combinations, constructions and arrangements of parts set forth, disclosed and claimed in the following specification considered in connection with the accompanying drawings.

In the drawings:

Fig. 1 is a front elevation of an embodiment of a paint brush holder constituting this invention.

Fig. 2 is a top plan view of the left end of Fig. 1.

Fig. 3 is a section on line 3—3 of Fig. 1.

Fig. 4 is a view similar to Fig. 3, but looking in the opposite direction and with the brush unsupported by the holding clip.

Fig. 5 is a fragmentary section on line 5—5 of Fig. 1.

Figs. 6 and 7 are side and plan views of the brush holding clip, and

Fig. 8 is an end plan view of a portable stand and a plurality of brush holding troughs supported thereon.

There is shown at 10 a trough which is V-shaped in cross section as shown in Figs. 3

and 4, and is preferably made of a single piece of sheet metal, the front wall 11 and the rear wall 12 being at a V angle to each other. A triangular piece 13 projects forwardly from each end of the rear wall 12 and is crimped to the end edge of front wall 11 as at 14: which crimp 14 may be also soldered or cemented if desired. The trough thus has its ends closed and acts as a receptacle, so that it may contain the bristle preserving liquid 15 such as linseed oil. The front wall 11 is bent inwardly upon itself as at 16 to stiffen and strengthen the trough and this bent flange may be doubled back on itself as shown. A similar flange 17 is formed on the upper edge of the rear wall 12, which wall may extend higher than the front wall as shown, while hook receiving openings 18 are formed in this higher rear wall. Any suitable number of metal strips or ears 19 secured adjacent the upper edge of the front wall 11 provide a support for a hinge rod 20 which may be removably held in place by cotter pins 21 through the ends thereof.

This rod 20 serves as a hinge pintle or support for a plurality of brush holding clips 22. These clips 22 are each formed of a piece of sheet metal having an end 23 looped back on itself, the loop 23 being adapted to be slid onto rod 20 before the rod is fixed in place by the cotter pins 21. The clip 22 is notched from one side at 24.

In operation, the clip 22 is arranged so that when not in use it is swung over and hangs down on the outside of the trough, as shown in Fig. 4. When it is desired to support a brush 25, the clip 22 is swung over to the position shown in Fig. 3 and the handle 26 of the brush is inserted in the notch 24, as shown in Fig. 3. The inner edge of the brush handle 26 may or may not lie against the free edge of flange 16 and the bristles 27 lie against the side of the trough, the handle being clamped and held by the opposite edges of the notch 24, the clamping action being automatic as the weight of the brush pulls the clamp downwardly and it automatically holds brushes with handles of different sizes. If the height of the oil in the tank varies it is very easy to adjust the brush up or down

so that the bristles 27 are properly covered by merely lifting the handle 26 or clip 22 and adjusting the handle in the clip. If the notch 24 is too wide for a small handle all that is necessary is to bend clip 22 at 28 so as to bring the edges of the notch closer together, the metal being a relatively soft metal.

From Fig. 3 it will be seen that the bristles 27 of the brush are held against a tapered side of the trough so that the bristle end of the brush is chiseled or the bristles adjacent their free ends are given a slight bend or curve inwardly to produce the taper or chisel shape desired at the end of the brush. This device takes the weight of the brush off the bristles, so that they are always held in the oil and they are always held to the proper shape while in the oil. The brush, therefore, can be kept indefinitely and is always ready for use, saving a great deal of money in brushes and always keeping the brushes in the best condition for use. When removing the brush from the trough, the bristles may be scraped against the free edge of flange 16 as it is withdrawn to remove the surplus oil, or it may also be scraped against the free edge of flange 17 for the same purpose.

Should the bristles be already bent out of shape, the brush 25 may be placed in the trough 10 unsupported by the clip 22 as in the position shown in Fig. 4, and the weight of the brush will press the bristles 27 against the inner sides of the trough. This will have the effect of straightening the bristles back to the proper shape so as to regain the desired chisel shape and straighten the bristles, and the brush may be left in this position until it has attained this shape, and then it may be placed on the clip as in Fig. 3.

The trough 10 can be mounted on hooks or nails on the wall in a paint shop, or a series of them can be mounted on a portable carrier or stand 30, as shown in Fig. 8. This stand 30 has upright members 31 supported on a base 32 and a plurality of hooks or nails 33 are placed in the upright 31, while a projecting nail or lug 34 is placed beneath each pair of hooks to engage the sides of the trough. The troughs are then placed with the openings 18 over hooks 33, and the lugs 34 hold the bottom outwardly from the upright so as to hold the trough with its lower edge over the lower trough so that any oil dripping from the upper trough will be caught by the lower.

In cleaning, the trough is scraped out, then a little gasoline poured in and lighted, burning it out clean.

Having thus set forth and disclosed the nature of this invention, what is claimed is:

1. A paint brush holder comprising a substantially V-shaped trough to hold a brush preserving liquid, means for gripping the handle to suspend a paint brush substantially vertically in said trough with the bristles of said brush in contact with one side of the

trough, and means for supporting the trough in upright position.

2. A paint brush holder comprising a substantially V-shaped trough for holding a liquid, means for supporting the trough in upright position, and means attached to said trough for detachably suspending a paint brush in said liquid with the bristles resting against a side wall of said trough to shape the brush.

3. A paint brush holder comprising a substantially V-shaped trough having side walls to engage the opposite sides of the bristle portion and taper it toward the free end, the ends of said trough being secured together to form a receptacle to hold brush preserving liquid, the top of the back wall of said trough being bent inwardly of the trough to form wiping edges for the brush bristles, and means for supporting the trough in upright position.

4. A paint brush holder comprising a substantially V-shaped trough, the side walls being adapted to engage opposite sides of the bristle portion of the brush and taper it toward the free end, the ends of said trough being secured together to form a receptacle to hold brush preserving liquid, the top of the rear edge of said trough being bent inwardly of the trough to form a wiping edge for the brush bristles, one of said tops being doubled back on itself to stiffen and strengthen the trough, and means for supporting the trough in upright position.

5. A paint brush holder comprising a substantially V-shaped trough, the side walls being adapted to engage opposite sides of the bristle portion of the brush and taper it toward the free end, the ends of said trough being secured together to form a receptacle to hold brush preserving liquid, the tops of said trough being bent inwardly of the trough to form wiping edges for the brush bristles, one of said tops being doubled back on itself to stiffen and strengthen the trough, a rod affixed along said stiffened edge and a brush holding clip hinged on said rod to project over said trough and slide longitudinally thereon.

6. A paint brush holder comprising a substantially V-shaped trough adapted to hold brush preserving liquid, means for engaging the handles for supporting brushes in said trough with the bristles resting against a side wall of said trough to press them together, said trough being composed of a single sheet of material, the back being bent at a V angle to the front side members projecting from the ends of the back and crimped about the ends of the front, one of the top edges of said trough being turned inwardly to said trough to form scraping means for the brushes, and means for supporting the trough in upright position.

7. A paint brush holder comprising a substantially V-shaped trough, means for sup-

porting brushes in said trough, said trough being composed of a single sheet of material, the back being bent at a V angle to the front, side members projecting from the ends of the back and crimped about the ends of the front, one of the top edges of said trough being turned inwardly to said trough to form scraping means for the brushes, the brush supporting means comprising a clip hinged to one side of said trough and adapted to project inwardly over said trough, said clip having a notch, the sides of said notch cooperating with the brush handle to detachably hold the brush in proper position.

8. A paint brush holder and shaper comprising a V-shaped trough, means for supporting the trough in upright position, a rod affixed to the front of the trough and extending longitudinally thereof, a brush clip hinged to said rod and adapted to project over said trough, said clip having a notch therein to receive the brush handle, the sides of said notch and the inside of the front of the trough cooperating with the brush to hold the brush in place and to shape the brush bristles as it is so held.

9. A paint brush holder and shaper comprising a V-shaped trough, the front of said trough having its edge bent over and doubled back on itself to provide a wiping edge and to stiffen the trough, a rod affixed to the front of the trough, a brush clip hinged to said rod and adapted to project over said trough, said clip having a notch therein to receive the brush handle, the sides of said notch and the inside of the front of the trough cooperating with the brush to hold the brush in place and to shape the brush bristles as it is so held, the back of said trough extending above the front and having a wiping edge turned inwardly therefrom, said back having openings therein to receive suspension hooks whereby said trough may be supported.

10. A paint brush holder comprising a substantially V-shaped receptacle suitable to carry a minimum of bristle preserving liquid at a maximum depth, means whereby said receptacle may be supported in upright position, the opposite sides of the V cooperating with the opposite sides of the bristle portion of a brush to properly shape the bristles.

11. A paint brush holder comprising a suitable holder for liquid, a brush holding means comprising a clip hinged to said holder said clip having a notch opening through one side thereof for insertion of the handle by a lateral movement, the edges of said notch cooperating with the handle of a brush to adjustably hold said brush.

12. A paint brush holder comprising a suitable holder for liquid, a brush holding means comprising a clip hinged to said holder said clip having a notch in one side thereof, the edges of said notch cooperating

with the handle of a brush to adjustably hold said brush, the clip being of bendable material whereby the edges of the notch may be brought closer together to fit a smaller brush.

70

13. A paint brush holder comprising a suitable receptacle for liquid and brush holding means on said receptacle comprising a rod, means for affixing said rod to said receptacle, a clip having a looped end adapted to be hinged on said rod and slide longitudinally thereon, said clip having a notch in one side thereof, the edges of said notch cooperating with the opposite sides of a brush handle to adjustably hold the same.

80

14. A paint brush holder comprising a V-shaped receptacle for a bristle preserving liquid, means whereby said receptacle may be supported in upright position, a brush supporting means on said receptacle comprising a rod extending longitudinally of the receptacle and a clip hinged to said rod and adapted to be projected over a top edge of the receptacle, said clip being slidable longitudinally on the rod and having a notch in one side thereof, the edges of said notch cooperating with the handle of the brush to hold the brush at a desired depth in the liquid.

85

15. A paint brush holder comprising a V-shaped receptacle for a bristle preserving liquid, means whereby said receptacle may be supported in upright position, a brush supporting means on said receptacle comprising a longitudinally extending rod and clip hinged to said rod and slidable longitudinally thereon, said clip having a notch in one side thereof, the edges of said notch cooperating with the handle of the brush to hold the brush at a desired depth in the liquid with the bristles in contact with the inside of said receptacle to shape the same.
